UNITED STATES PATENT OFFICE.

WILLIAM E. SEELYE, OF SAULT STE. MARIE, ONTARIO, CANADA.

TUG AND TRACE FASTENER.

1,082,215.

Specification of Letters Patent. Patented Dec. 23, 1913.

Application filed July 2, 1913. Serial No. 777,042.

To all whom it may concern:

Be it known that I, WILLIAM E. SEELYE, a citizen of the United States, residing at Sault Ste. Marie, in the Province of Ontario and Dominion of Canada, have invented a new and useful Tug and Trace Fastener, of which the following is a specification.

This invention relates to a trace fastener.

An object of the present invention is to provide a trace fastener which will remain in a locked position and will also remain in an unlocked manner when so positioned.

A further object is to provide a trace fastener which may be easily installed upon any swingletree already in use, will not materially weaken the same, and is prevented from becoming accidentally unlocked.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the drawings accompanying this specification and forming a part thereof, the preferable form of my invention is illustrated, in which:—

Figure 1 is a top view of a swingletree with a trace fastener positioned thereon and my improved fastening means secured thereto. Fig. 2 is an end view of the swingletree and showing the trace in elevation. Fig. 3 is a longitudinal sectional view taken through the axis of the swingletree. Fig. 4 is a somewhat similar view showing the trace fastened in an unlocked position. Fig. 5 is a perspective view of the fastener.

Referring to the drawings in which similar reference numerals designate corresponding parts throughout the several views, 1 is the body portion of the device which may fit over the end of a swingletree or be formed as a part thereof, the end of which is bifurcated or provided with a longitudinally extending slot 2 in which my improved trace fastener is secured. The trace 3 is provided with the usual aperture 4 therein and which aperture is of sufficient size to fit over the end of the swingletree as illustrated in Figs. 1, 3 and 4. The position of the trace 3 upon the swingletree 1 is limited by a suitable stop in the form of an outwardly

projecting boss or lug 5 so that when it is desired to position the tug or trace upon a swingletree no relative adjustment of the two is necessary, the tug or trace being slipped upon the swingletree until it contacts with the stop 5. Located approximately central of the slot 2 taken with respect to the vertical is a wide thin bar 6 which is adapted to secure the latch 7 to the swingletree and mount the same for rotatory and transitory motion.

The latch 7 comprises a long narrow plate 8 the lower extremity of which is provided with the hooked portion 9, the purpose of which is to engage the bar 6 and to prevent the said latch from becoming displaced or removed therefrom. Spaced a distance from the hooked portion 9 approximately equal to the width of the bar 6 is an outwardly extending lug 10 which supports the latch when in a vertical position as illustrated in Fig. 3 and also coacts with the hooked portion 9 and the bar 6 to prevent the latch from becoming displaced from the slot 2 of the swingletree. The upper portion 11 of the latch is adapted to extend beyond the end of the swingletree when the latch is in a horizontal position as illustrated in Fig. 4 and affords gripping means whereby the latch may be rotated to a vertical position prior to the dropping of the same into a locked position. The end wall 12 of the slot is spaced a distance away from the end of the wide bar 6 a distance slightly in excess of the thickness of the latch and is provided with an arcuated portion 13 which allows for the rotating of the hooked portion 9 about the bar 6 as a center in order to pass from a vertical to a horizontal position. The latch member is provided with a channel 14 extending along one face thereof adjacent the lug 10 and which is adapted to engage the edge of the bar 6 and thereby be prevented from jouncing upwardly which would tend to throw the same out of a locked position.

In the practical use of my improved trace fastener the latch is first brought to a horizontal or extended position as illustrated in Fig. 4 and the trace 3 passed over the end of the swingletree and abuts against the boss or stop 5. The end 11 of the latch is then gripped and manually rotated about the hooked portion 9 as a center until the same assumes a position as illustrated in dotted lines in Fig. 4. The latch is then released

and dropped by gravity into a locked position as illustrated in Fig. 3 in which the channel 14 engages the end wall of the strip 6 and the trace holds the same in such re-
 5 lation. The particular advantage of con-
 structing the latch and the securing bar in
 the manner as I have described will be
 clearly apparent especially when it is pointed
 10 out that the latch will remain in the ex-
 tended position as illustrated in Fig. 4 so
 that in order for the trace to be placed upon
 the swingletree the latch is first set in the
 15 said position and the trace then placed over
 the swingletree without interference from
 the latch. The latch is then manually ro-
 tated and dropped into its locked position
 20 in which position the body portion of the
 latch extends below the swingletree to a dis-
 tance approximately equal to that which it
 25 extends thereabove, the result being that an
 even pressure or holding effect is produced
 upon all portions of the trace. Furthermore
 mention is made of the fact and con-
 siderable importance attached thereto, that
 30 with the structure as herein described it is
 not necessary that the slot extend beneath
 the final position of the trace so that the
 swingletree will not be in any way weak-
 ened at those points at which stress is
 35 brought to bear thereon.

What I claim is:—

1. A trace fastener comprising a latch,
 including a lower hooked end, and a lug out-
 35 standing centrally therefrom, and a sup-
 porting bar for said latch coacting with the
 said hooked end and the said lug to hold
 the latch movably secured thereto, said latch
 member adapted to assume a horizontal pos-
 40 sition for the passing of a trace thereover,
 said latch member adapted to assume a ver-
 tical position for the locking of the trace
 therebehind.

2. The combination with a swingletree
 provided with a slot extending therein, of
 45 a bar extending thereacross and spaced a
 distance from the end of the slot, a latch
 member comprising a body portion, a hook-
 shaped end, and a lug outstanding there-
 from, fitting between the end of the slot
 50 and the said bar, said latch member coact-
 ing with the said bar, the hooked end and
 outstanding lug engaging the said bar and
 preventing the accidental displacement of
 the latch member therefrom, said latch mem-
 55 ber adapted to assume a horizontal position
 for the passing of a trace thereover, and
 adapted to assume a vertical position sup-
 ported by the lug coacting with the bar to
 hold the trace against displacement.

3. The combination of a swingletree pro-
 vided with a slot extending therein, a bar
 extending across said slot at a slight dis-
 tance from the end thereof, a latch member
 60 fitting between the said bar and the slot
 end, said latch member provided with a
 hook-shaped end and an outstanding lug
 spaced a distance therefrom approximately
 65 equal to the width of the said bar, the
 hooked end and outstanding lug coacting
 with the said bar to prevent the accidental
 70 displacement of the said latch member, said
 latch member adapted to assume a horizon-
 tal position for the passing of a trace there-
 over, said latch member adapted to assume
 75 a vertical position for the locking of the
 trace upon the said swingletree.

4. In a trace fastener the combination of
 a swingletree provided with a slot extend-
 ing therein, a bar extending across the said
 slot and spaced a distance from the end
 80 thereof, a latch member mounted for rota-
 tion and translation within the slot behind
 the bar, said bar prohibiting the removing
 of the said latch member, said member adapt-
 ed to translate and rotate into a horizontal
 85 unlocked position, and into a vertical locked
 position.

5. In a device of the class described the
 combination of a swingletree provided with
 a slot extending therein, a trace stop re-
 90 moved a material distance from the end of
 said slot, a wide thin bar extending across
 the said slot and spaced a slight distance
 from the end thereof, a latch member fitting
 within the slot behind the bar, said latch
 95 member provided with a hook-shaped end,
 an outstanding lug spaced a distance from
 the end approximately equal to the width of
 the bar, the opening defined by the slot in
 the bar mounting the latch member for
 100 translation and rotation and prohibiting the
 removing thereof, said latch member pro-
 vided with a channel adjacent the said pro-
 jecting lug adapted to interlock with the
 edge of the said bar, said latch member
 105 adapted to assume a horizontal position for
 the passing of a trace thereover, said latch
 member adapted to assume a vertical posi-
 tion supported upon the bar by the said
 lug for the locking of the trace upon the
 110 said swingletree.

In testimony that I claim the foregoing
 as my own, I have hereto affixed my signa-
 ture in the presence of two witnesses.

WILLIAM E. SEELEYE.
